poration of Massachusetts

Application June 19, 1940, Serial No. 341,333

8 Claims. (Cl. 51—95)

The invention relates to grinding machines, and more particularly to a hydraulically operated multi-purpose grinding machine.

One object of the invention is to provide a simple and thoroughly practical improved universal or multi-purpose grinding machine. Another object of the invention is to provide a multi-purpose grinding machine in which the wheel head may be angularly adjusted and fed in a direction normal to the axis of the work piece or in which the wheel slide support may be angularly adjusted so that the grinding wheel may be fed in a direction at an angle to a plane normal to the work axis. A further object of the invention is to provide an improved multi-speed manually operable wheel feeding mechanism. Another object of the invention is to provide an improved multi-speed manually operable traversing mechanism for traversing the work supporting table longitudinally. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention:

Fig. 1 is a front elevation of the improved grinding machine;

Fig. 2 is a right-hand end elevation, on an enlarged scale, of the grinding machine shown in Fig. 1, having parts broken away and shown in section to more clearly show the wheel feeding mechanism;

Fig. 3 is a fragmentary sectional view, on an enlarged scale taken approximately on the line 3—3 of Fig. 2, showing the wheel slide supporting and adjusting mechanism;

Fig. 4 is a fragmentary sectional view, on an enlarged scale, taken approximately on the line 4—4 of Fig. 1;

Fig. 5 is a fragmentary cross sectional view, on an enlarged scale, taken approximately on the line 5—5 of Fig. 1, showing the manually operable table traverse mechanism;

Fig. 6 is a fragmentary sectional view, taken approximately on the line 6—6 of Fig. 5;

Fig. 7 is a fragmentary view, showing the manually operable change gear mechanism for the wheel feeding mechanism; and

Fig. 8 is a fragmentary cross-sectional view, 55

on an enlarged scale, taken approximately on the line 8—8 of Fig. 4.

As illustrated in the drawings, a grinding machine is provided having a base 10 which supports a longitudinally reciprocable work supporting table 11 on the usual flat way 12 and V-way 13 for a longitudinal reciprocatory movement relative to the base 10.

A rotatable work support is provided for the table 11 comprising a headstock 14 and a footstock 15 which are provided with work supporting centers 16 and 17, respectively. The headstock 14 is preferably a motor driven headstock having an electric motor 18 mounted on the upper surface of the headstock 14. The motor is provided with a multi-V-grooved pulley 19 which is connected by multiple V-belts 20 with a pulley 21 which may be mounted on the left-hand end of a headstock spindle 22.

A rotatable grinding wheel 25 is supported on the left-hand end of a wheel spindle 26 (Fig. 1). The wheel spindle 26 is rotatably supported in suitable bearings (not shown) in a wheel head 27. A driving mechanism is provided for rotating the grinding wheel 25 comprising an electric motor 28 having a driving pulley 29 which is connected by multiple V-belts 30 with a pulley 31 mounted on the right-hand end of the wheel spindle 26 (Fig. 1). The motor 28 is preferably mounted on a motor support 32 which is pivotally supported on a shaft 33 mounted on the rear end of the wheel head 27. The pivotal mount for the motor provides means whereby the driving belt 30 may be tensioned as desired.

The wheel head 27 is supported on a transversely movable wheel slide 35. The wheel slide 35 is supported for a transverse movement on a V-way 36 and a flat way 37 formed between the wheel slide 35 and a wheel slide base 38. In order to provide a swivel adjustment for the wheel spindle relative to the slide, a swivel adjustment is provided between the wheel head 27 and the wheel slide 35. The wheel head 27 is provided with an enlarged circular base portion 40 which is provided with a downwardly projecting annular shaped projection 41 which mates with a correspondingly shaped aperture 42 formed in the upper surface of a transversely adjustable member 42a. The member 42a is transversely adjustable on the upper surface of the wheel slide 35. A binder bolt 43 has its enlarged head 44 held in a T-shaped slot 45 formed in the upper portion of the wheel slide 35. The binder bolt 43 passes through a central aperture 46 in the wheel head member 27 and a central aperture

in the member 42a. The binder bolt 43 is provided with a transversely extending tapered aperture 47 through which a tapered portion 48 of a binding screw 49 passes.

It will be readily apparent from the foregoing disclosure that when the clamping screw 49 is tightened, that is, the screw turned so that the tapered portion 48 moves toward the right (Fig. 3), the tapered portion 48 of the screw 49 produces an upward movement of the binder bolt 43 so as to lock the head 27 rigidly in position on the wheel slide 35. The periphery of the enlarged portion 40 of the grinding wheel head 27 and its supporting portion of the wheel slide 35 may be graduated, if desired, so that the grinding wheel head 27 may be angularly adjusted for a grinding operation when desired. This adjustment is utilized where it is desired to adjust the position of the wheel axis angularly relative to the work axis so that a tapered portion of the work piece may be ground with a true cylindrical face on the grinding wheel. When the binder bolt 43 is loosened to facilitate an angular adjustment of the wheel head 27, a rapid transverse positioning movement of the wheel head 27 may be obtained by sliding the wheel head 27 together with its supporting member 42a transversely on the wheel slide 35 to position the grinding wheel 25 in setting up the machine, after which the binder bolt 43 may be locked to clamp the parts in adjusted position.

In certain types of grinding, it is desirable to provide an angular adjustment for the wheel slide so that instead of traveling transversely in a path normal to the work axis, it may be moved transversely in a path at an angle thereto. To accomplish this result, the wheel slide base 38 is provided with a downwardly projecting flange 52 which mates with a cylindrical surface 53 formed on a plate 54 which is fixedly mounted on the rear portion of the base 10. The plate 54 is provided with a circular shaped T-slot 55. Clamping screws 56 and 57 are provided with enlarged heads which slide in the T-slot 55 and pass through apertures 58 and 59 formed in the wheel slide base 38 on diametrically opposite sides thereof. It will be readily apparent from the foregoing disclosure that by loosening a nut 60 and a nut 61, the wheel slide base 38 may be rotated to position the V-way 36 and flat way 37 at an angle other than normal to the work axis. The peripheral surface 53 may, if desired, be graduated so that the position of the V-way 36 and flat way 37 of the wheel slide base 38 may be adjusted to the desired angular position, after which the nuts 60 and 61 may again be clamped to lock the wheel slide base 38 in adjusted position. It will be readily apparent from the foregoing disclosure that the wheel slide base 38 may be adjusted in either direction and through 360° if desired.

Manually operable table traverse

A manually operable table traverse mechanism is provided, preferably of a multi-speed type, whereby the table 11 may be traversed manually at a comparatively rapid rate to position the table and a work piece supported thereon relative to the grinding wheel 25, or may be traversed at a relatively slow rate of speed during a grinding wheel truing operation. This mechanism may comprise a manually operable hand wheel 70 which is provided with an enlarged hub 71. The hand wheel hub 71 is slidably keyed to an input shaft 72 of a speed reduction unit 73.

The speed reduction unit 73 may be any of the well known speed reducing units. The unit illustrated, however, is the well known "heliocentric" speed reduction unit manufactured by the Universal Gear Corporation of Indianapolis, Indiana. The "heliocentric" unit 73 is rotatably supported in bearings 74 and 75 which are carried by an apron 76. The driven or input shaft 72 of the "heliocentric" unit 73 carries a pair of eccentrics 62 and 62a. A rotatable output or driven shaft 77 is fixedly mounted to a rotatable plunger holder 63 which travels within a stationary internal gear or rack member which is preferably divided into two parts, namely, the internal annular racks 64 and 64a. The plunger holder 63 travels within the stationary racks 64 and 64a at the rate of one tooth for each rotation of the input shaft 72. The plunger holder 63 is slotted radially and carries a plurality of reciprocable plungers 65 and 65a which are arranged to work into and out of mesh with the teeth of the stationary internal racks 64 and 64a, respectively. The racks 64 and 64a are keyed to the casing, having the appearance of an internal ring gear, but with definitely differing tooth shapes, the teeth of the racks 64 and 64a being substantially wedge-shaped. Due to the working contact between the arrow-pointed plungers 65 and 65a and the teeth of the racks 64 and 64a, respectively, a combination sliding and rolling wedge action is obtained, forcing rotation with a minimum friction to the plunger holder 63 and the output or driven shaft 77. The input eccentrics 62 and 62a force the plungers out under load. A pair of retracting rings 66 and 66a ride in notches formed within the plungers 65 and 65a, respectively, to hold back on the no-load part of the cycle of operation.

A single set of plungers and stationary racks 40 may be employed, but for the maximum smoothness of operation and balance of the working parts, a universal "heliocentric" reducer is employed, having two eccentrics 62 and 62a, as illustrated, each of which actuates a set of plungers 45 65 and 65a, respectively, in operative engagement with a pair of stationary racks 64 and 64a, respectively. Each set of plungers 65 and 65a is timed directly opposite or 180 degrees apart and has a carrying arc of approximately 120 degrees. 50 The total effect is a balanced distribution of power over two-thirds of the complete cycle so that a balanced and uniform slow rotation of the output or driven shaft 77 is transmitted to rotate the gear 86 and thereby transmit a traversing movement to the rack 87 and table 11.

The heliocentric unit 73 is rotatably supported in bearings 74 and 75 which are carried by an apron 76. The output shaft 77 is provided with a gear 78 which meshes with a rotatable idler gear 79 which is rotatably supported on a shaft 80 (Fig. 6). The gear 79 meshes with a gear 81 which is keyed on a rotatable shaft 82. The shaft 82 is journalled in bearings 83 and 84 which are supported in a bracket 85 fixedly mounted on the apron 76. The shaft 82 rotatably supports a gear 86 which meshes with a rack bar 87 depending from the under side of the work supporting table 11. The shaft 82 also supports a clutch member 88 which is slidably keyed thereon and which is arranged to be moved into and out of mesh with clutch teeth 89 formed integral with the gear 86. When the clutch 88 is disengaged from the clutch teeth 89, no rotary motion may be transmitted between the shaft 88 and the gear 86.

It is desirable that during the hydraulic traverse of the table 11, the hand traverse mechanism be rendered inoperative. In order to accomplish this result, a hydraulically operated mechanism is provided comprising a cylinder 90 having a slidably mounted piston 91 therein which is arranged to engage and actuate a rock arm 92. The rock arm 92 is pivotally supported by a stud 93 which is in turn fixedly supported on the bracket 85. The upper end of the arm 92 is yoke-shaped and is provided with spaced diametrically opposed studs 94 which ride in a groove 95 formed in the periphery of the clutch member 88. A spring 96 is interposed between the lower end of the rock arm 92 and a depending projection 97 formed integral with the cylinder 90, normally tending to hold the clutch member 88 in engagement with the clutch teeth 89 so that a hand traverse of the work supporting table 11 may be obtained by rotation of the hand wheel 70. The admission of fluid under pressure to the cylinder 90 serves to disengage the clutch member 88.

A clutch mechanism is provided between the hand wheel 70 and the unit 73, comprising an internal ring gear 98 which is fixedly mounted to the hub 71 to rotate with the hand wheel 70. A gear 99 of the same pitch diameter as the gear 98 is fixedly mounted to the heliocentric casing 73. When the hand wheel 70 is in the position illustrated in Fig. 5, the gear 98 meshes with the gear 99, operatively connecting the hand wheel 70 with the housing 73 of the heliocentric unit 73 so that when a rotary motion is imparted to the hand wheel 70, it will rotate the heliocentric unit and transmit a one to one rotation between the hand wheel 70 and the gear 78 which in turn transmits rotation through the clutch members 88-89 to rotate the gear 86 and thus impart a longitudinal traversing movement to the rack bar 87 and the work supporting table 11.

If a slow traversing movement of the table 11 is desired, the hand wheel 70 is moved toward the left (Fig. 5) to disengage the ring gear 98 from the gear 99. A binder or clamping screw 69 is tightened to lock the heliocentric casing 73 relative to the apron 76. In this position of the parts, any rotation of the hand wheel 70 is transmitted through the input shaft 72 which operates through the speed reduction unit to impart a slow rotary motion to the output shaft 77. The output shaft 77 in turn transmits a rotary motion through the gear mechanism above described to the clutch parts 88 and 89 to rotate the gear 86 and transmit a slow traversing movement to the rack bar 87 and the work supporting table 11.

Grinding wheel feeding mechanism

A grinding wheel feeding mechanism is provided for feeding the grinding wheel slide 35 together with the grinding wheel 25 transversely toward and from the work axis. This mechanism may comprise a half nut 100 depending from the under side of the slide 35. The half nut 100 meshes with a rotatable cross feed screw 101 which is rotatably journaled in bearings 102 and 103 in the wheel slide base 38. Adjusting screws 104 and 105 are provided whereby the end thrust of the feed screw 101 may be taken up. A bevel gear 106 is keyed on the reduced end portion of the feed screw 101. The bevel gear 106 meshes with a bevel gear 107 which is keyed on the upper end of a rotatable shaft 108. The shaft 108 is journaled in a bearing 109 which is arranged so that the axis of the shaft 108 coincides with the axis of adjustment of the wheel slide base 38.

A bevel gear 110 is fixedly mounted on the lower end of the shaft 108. The bevel gear 110 meshes with a bevel gear 111 which is keyed on the rear end of a rotatable shaft 112. The shaft 112 is journaled in bearings 113, 114, 115, 116 and 117 (Fig. 2). The shaft 112 supports a cluster gear 120 comprising a large diameter gear 121 and a smaller diameter gear 122 which mesh with a gear 123 and a gear 124, respectively, supported on an output shaft 125 of a speed reduction unit to be hereinafter described. The gear 123 is rotatably supported on a reduced end portion of the shaft 125 and is provided with clutch teeth 126 which are arranged to be engaged by clutch teeth 127. The clutch teeth 127 are formed integral with a slidably mounted clutch member 128 which is slidably keyed to the shaft 125. The gear 124 is formed integral with the clutch member 128. In the position of the parts as illustrated in Fig. 4, a rotary motion of the shaft 125 will be transmitted through the gear 124 to the gear 122 to rotate the shaft 112 and thus transmit a comparatively fast rotation to the feed screw 101 to advance the grinding wheel either toward or from the work support, depending upon the direction of rotation of the hand wheel 145.

If it is desired to rotate the feed screw 101 at a slow speed, the clutch member 128 is moved toward the right (Fig. 4) so that the clutch teeth 127 engage the clutch teeth 126. During this movement, the gear 124 slides out of mesh with the gear 122. In this position of the parts, rotation of the shaft 125 will be transmitted through the clutch member 128, the clutch teeth 127, the clutch teeth 126, to impart a rotary motion to the gear 123 to rotate the gear 121 and, through the mechanism previously described, to rotate the feed screw 101 at a comparatively slow rate of speed.

A manually operable mechanism is provided for actuating the clutch member 128 from the operator's control station in front of the machine. The clutch member 128 is provided with a groove 129. A lever 130 is pivotally mounted on a stud 131 which is in turn fixedly supported by a bracket 132 formed integral with an apron 133. The right-hand end of the lever 130 (Fig. 7) is yoke-shaped and is provided with diametrically opposed shoes 134 and 135 which are positioned on diametrically opposite sides of the clutch member 128 and which ride within the groove 129 formed thereon. The left-hand end of the lever 130 (Fig. 7) is connected by a stud 136 with a link 137. The link 137 is in turn connected by a stud 138 with a slidably mounted shaft 139. The shaft 139 slides longitudinally within a bearing surface 140 formed within the apron 133. A manually operable actuating knob 141 is fixedly mounted on the outer end of the shaft 139 and projects from the front of the machine base. It will be readily apparent from the foregoing disclosure that a downward movement of the knob 141 (Fig. 7) will rock the lever 130 in a counterclockwise direction so as to throw the gear 124 out of mesh with the gear 122 and at the same time throw the clutch teeth 127 into engagement with the clutch teeth 126 when it is desired to impart a slow rotary movement to the feed screw 101 as above described.

In order to provide a relatively slow rotation of the output shaft 125, a manually operable hand wheel 145 is provided. The hand wheel 145 is connected in a manner to be hereinafter described

to an input shaft 146 of a heliocentric speed reducing unit 147 (Fig. 4). The speed reduction unit 147 is the well known "heliocentric" speed reduction unit similar in construction to the one previously described in connection with the table traversing mechanism. The driven or input shaft 146 carries a pair of eccentrics 148 and 149, respectively. The rotatable output shaft 125 is fixedly mounted to a rotatable plunger holder 150 which travels within a stationary internal gear or rack member which is preferably divided into two parts, namely, the internal racks 151 and 152. The racks 151 and 152 within the unit casing 147 have the general aspect of an internal ring gear but with definitely different tooth shapes, the teeth of the racks 151 and 152 being substantially wedge-shaped. Due to the working contact of the sets of arrow-pointed plungers 153 and 154 and the teeth of the racks 151 and 152, respectively, a combination sliding and rolling wedge action is obtained, forcing rotation with a minimum friction to the plunger holder 150 and the output or driven shaft 125. The input eccentrics 148 and 149 force the plungers 153 and 154 out under load. A pair of retracting rings 155 and 156 ride in notches formed within the side faces of the plungers 153 and 154, respectively, to hold them back on the no load part of their cycle of operation.

A single "heliocentric" unit or set of plungers and stationary racks may be employed, but for a maximum smoothness of operation and balance of the working parts, a universal heliocentric reducer is employed, having the two eccentrics 148 and 149 as illustrated and described above, each of which actuates a set of plungers 153 and 154, respectively, and in operative engagement with a pair of stationary racks 151 and 152, respectively. Each set of plungers is timed directly opposite or 180 degrees apart and has a carrying arc of approximately 120 degrees. The total effect is a balanced distribution of power over two-thirds of the complete cycle so that a balanced and uniform slow rotation of the output or driven shaft 125 is transmitted to rotate the feed screw 101 through the gear mechanism above described.

The heliocentric unit 147 is rotatably supported in bearings 157 and 158 in an apron 159. A binder screw 160 is provided for locking the unit 147 against rotation. A gear 161 is fixedly mounted to the hub portion 162 projecting from the unit 147. The manually operable feed wheel 145 is supported on the hub 162 and is arranged to be connected with the input shaft 146 of the unit 147 by means of an index mechanism to be hereinafter described. An arm 163 is keyed to the input shaft 146. The arm 163 carries a spring-pressed index plunger 164 which is arranged to engage one of a series of holes 165 formed in a circular path on the front face of the hand wheel 145. A knob 166 is provided for retracting the plunger 164 when desired to adjust the position of the shaft 146 relative to the hand wheel 145.

A clutch mechanism is provided between the hand wheel 145 and the input shaft 146 so that the hand wheel may be readily reset when desired. A gear 167 is fixedly mounted on the hand wheel 145. The gear 167 is an internal gear of the same pitch diameter as the gear 161. The hand wheel 145 is normally held in the position illustrated in Fig. 4 by means of a plurality of symmetrically arranged, spring pressed plungers 168 (only one of which is shown in Fig. 4). These plungers serve normally to maintain the hand

wheel in its left-hand position (Fig. 4) with the gear 167 meshing with the gear 161 and the spring-pressed plunger 164 engaging one of the index holes in the hand wheel 145. When it is desired to reset the hand wheel, it is moved toward the right (Fig. 4) on the hub 162 of the unit 147 against the compression of the plungers 168. This movement disengages the gear 161 from the gear 167 so that the hand wheel may be rotated to transmit a rotary motion to the input shaft 146 while the housing 147 of the heliocentric unit is held stationary so as to impart a relatively slow rotation to the shaft 125 and thereby transmit a correspondingly slow rotary motion to the feed screw 101.

A stop mechanism is provided comprising a stop abutment 170 which is pivotally supported by a stud 171 on the apron 159. When desired, the stop abutment 170 may be rotated in a clockwise direction into an inoperative position so that the wheel 145 may be rotated continuously without interference of the abutment. The hand wheel 145 supports a rotatable stop pin 172 having an enlarged head 173 half of which is slabbed off on one side so as to provide a semi-cylindrical stop surface 175 (Figs. 4 and 8). When the hand wheel 145 is rotated in a counterclockwise direction to produce an infeeding movement of the grinding wheel, the slabbed-off semi-cylindrical surface 175 moves into engagement with the stop abutment 170 (Fig. 8), thus positively limiting the rotation of the hand wheel 145 to stop the forward feeding movement of the grinding wheel slide 27 and the grinding wheel 25. When the hand wheel is rotated in a clockwise direction to produce a rearward movement of the slide 27 and the grinding wheel 25, the slabbed-off surface 174 of the stud 172 moves into position 174a (Fig. 8) whereupon continued movement produces a camming action between the slabbed-off surface 174 and the side face of the stop abutment 170 so as to rock the stop abutment 170 to an inoperative position and thus facilitate rotation of the hand wheel 145 to the desired extent. This enables the removal of the grinding wheel to a rearmost position as determined by the operator. After the ground piece of work has been removed from the machine and a new piece of work placed thereinstead, the hand wheel 145 may then be rotated in a counterclockwise direction to advance the wheel slide 27 and grinding wheel 25 toward the peripheral surface of the work piece. When the grinding wheel is in close proximity to the peripheral surface of the work piece, the stop abutment 170 is then swung in a counterclockwise direction into the position illustrated in Fig. 4 so that on the last rotation of the hand wheel, the semi-cylindrical stop surface 175 will be in the path of the stop abutment 170 to limit 60 the infeeding movement of the grinding wheel.

In case it is desired to compensate for wheel wear, the feed wheel may be rotated until the semi-cylindrical surface 174 engages the stop abutment 170, after which the plunger 164 may be moved toward the left (Fig. 4) to disengage it from the hole 165, after which the arm 163 may be rotated in the desired direction one or more holes to reset the position of the grinding wheel 70 relative to the stop abutment and thus compensate for wear on the wheel due to the grinding operation. This adjustment is also useful during a grinding wheel truing operation and serves as a feeding mechanism whereby the grinding wheel 75 25 and its supporting slide 35 may be advanced

by the desired and predetermined amount for a truing operation.

The operation of the improved grinding machine will be readily apparent from the foregoing disclosure. A work piece is mounted on the headstock 16 and footstock center 17, the grinding wheel and its supporting slide is adjusted in accordance with the nature of the work to be ground, that is, with the grinding wheel axis parallel to the axis of the work piece so that a feeding movement may be had in a path normal to the work axis. The wheel head may be adjusted angularly to present a true cylindrical face for the grinding of a frusto-conical surface on the work piece or, if desired, the wheel slide base may be angularly adjusted so that a feeding movement may be obtained which is at an angle to a path normal to the work axis. The work table 11 may then be traversed longitudinally by rotation of the manually operable hand wheel 70 either at a fast or a slow rate under manual power or may be traversed or reciprocated longitudinally by power as desired. The grinding wheel 25 may then be fed transversely either at a fast or a slow rate of feed by rotation of the manually operable feed wheel 145.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a base, a longitudinally movable rotatable work support and a transversely movable rotatable grinding wheel, a transversely movable wheel slide on said base, a transversely movable supporting member on said slide, an angularly adjustable head on said member to support said grinding wheel, said angularly adjustable wheel head and supporting member serving to facilitate a rapid transverse and angular movement of the wheel head and grinding wheel relative to said slide, means to clamp said head and member in adjusted position, a swivel adjustment between said slide and said base whereby said slide may be angularly positioned relative to the base, and a wheel feeding mechanism operatively connected to move said slide transversely in any adjusted position thereof.

2. In a grinding machine having a base, a longitudinally movable rotatable work support and a transversely movable rotatable grinding wheel, a transversely movable wheel slide on said base, a transversely movable supporting member on said slide, an angularly adjustable head on said member to support said grinding wheel, said angularly adjustable wheel head and supporting member serving to facilitate a rapid transverse and angular movement of the wheel head and grinding wheel relative to said slide, means to clamp said head and member in adjusted position, a swivel adjustment between said slide and said base whereby said slide may be angularly positioned relative to the base, and a wheel feeding mechanism including a nut and feed screw operatively connected to move said slide transversely in any adjusted position thereof.

3. In a grinding machine having a base, a longitudinally movable rotatable work support and a transversely movable rotatable grinding wheel, a transversely movable wheel slide on said base, a transversely movable supporting member on said slide, an angularly adjustable head on said member to support said grinding wheel, said angularly adjustable wheel head and supporting member serving to facilitate a rapid angular and transverse adjustment of the grinding wheel, means to clamp said head and supporting member in adjusted position on said slide, a swivel adjustment interposed between said slide and said base whereby the slide may be angularly adjusted relative to the base, a nut and screw feeding mechanism, and a manually operable feeding mechanism on the base, driving connections between said feeding mechanism and the feed screw comprising a rotatable shaft which coincides with the axis of said swivel adjustment whereby the wheel slide may be adjusted transversely in any angular position of said slide.

4. In a grinding machine having a base, a transversely movable wheel slide on said base, a transversely movable supporting member on said slide, a rotatable grinding wheel, an angularly adjustable wheel head on said member to support said grinding wheel, means to clamp said head and supporting member in adjusted position on the slide, a swivel support interposed between the wheel slide and base, and a wheel feeding mechanism for said slide comprising a nut and screw mechanism to move said slide, a rotatable shaft positioned to coincide with the axis of the slide swivel adjustment, gearing connecting said shaft with said screw, and a manually operable feed mechanism on the base to rotate said shaft and thereby feed said grinding wheel transversely in any adjusted position of the wheel head and wheel slide.

5. In a grinding machine in accordance with claim 4, the combination with the parts and features therein specified, of a micrometer adjusting mechanism combined with an adjustable stop mechanism whereby the wheel slide may be moved to an inoperative position through an indefinite distance, said mechanism being arranged so that the wheel slide advance may be stopped at the desired and predetermined position on the next infeeding movement.

6. In a grinding machine having a base, a longitudinally movable work support and a transversely movable rotatable grinding wheel, a transversely movable wheel slide on said base, and a wheel feeding mechanism therefor including a nut and screw, an axially movable rotatable hand feeding wheel, a speed reduction unit interposed between the feed wheel and nut and screw mechanism, and a clutch between said hand wheel and the speed reduction unit which is actuated by axial movement of said hand wheel, said mechanism and unit being arranged when the clutch is engaged to connect the hand wheel to rotate the feed screw rapidly and when the clutch is disengaged to rotate the feed screw slowly.

7. In a grinding machine having a base, a longitudinally movable work support and a transversely movable rotatable grinding wheel, a longitudinally movable work table including a manually operable table traverse mechanism comprising an axially movable rotatable hand traverse wheel, a rack and gear mechanism operatively connected to move said table, a rotat-

ably mounted speed reduction unit interposed between the traverse wheel and the rack and gear mechanism, means to hold said unit against rotation when desired, and a clutch between the traverse wheel and speed reduction unit which is actuated by an axial movement of said wheel, said parts being arranged so that when the clutch is engaged, rotation of the hand wheel serves to rotate the entire unit to produce a relatively fast traversing movement of the table.

8. In a grinding machine having a base, a longitudinally movable work support and a transversely movable rotatable grinding wheel, a longitudinally movable work table including a manually operable table traverse mechanism comprising an axially movable rotatable hand

traverse wheel, a rack and gear mechanism operatively connected to move said table, a rotatably mounted speed reduction unit interposed between the traverse wheel and the rack and gear mechanism, means to hold said unit against rotation when desired, and a clutch between the traverse wheel and speed reduction unit which is actuated by an axial movement of said wheel, said parts being arranged so that when the clutch is disengaged and the speed reduction unit held against rotation, a rotary movement of the hand wheel serves through the speed reduction unit to transmit a relatively slow traversing movement to the table.

JOHN I. GARSIDE.
